DESIGN FOR A RATION POINT HOLDER

Annie Porche, Houma, La.

Application February 24, 1944, Serial No. 112,690

Term of patent 7 years

(Cl. D58—12)

To all whom it may concern:

Be it known, that I, Annie Porche, a citizen of the United States, residing at Houma, in the Parish of Terrebonne and State of Louisiana, have invented a new, original, and ornamental Design for a Ration Point Holder, of which the following is a specification, reference being had to the accompanying drawing, forming a part thereof.

Figure 1 is a top plan view of a ration point holder showing my new design;

Figure 2 is a side elevational view thereof;

Figure 3 is an end elevational view thereof.

I claim:

The ornamental design for a ration point holder, as shown.

ANNIE PORCHE.
